UNITED STATES PATENT OFFICE.

JOEL SANDER, OF HAMBURG, GERMANY, ASSIGNOR TO HIMSELF AND
CHRISTIAN FRIEDERICH FRANZ STEIN, OF SAME PLACE.

WIND-WHEEL.

SPECIFICATION forming part of Letters Patent No. 234,617, dated November 16, 1880.

Application filed April 8, 1880. (No model.) Patented in England January 23, 1880, and in Belgium February 4, 1880.

To all whom it may concern:

Be it known that I, JOEL SANDER, of Hamburg, in the Empire of Germany, have invented certain new and useful Improvements 5 in Wind-Wheels, of which the following is a specification.

My invention consists in a wind mill or wheel in which the blades are arranged to turn upon horizontal axles which extend upon 10 opposite sides of a central vertical shaft, and two or more pairs of such blades are arranged, one pair above another, upon said vertical shaft. Each blade consists of a single piece or surface hinged to the horizontal shaft above the 15 center of the blade, so that the weight of the lower side thereof always preponderates and tends to turn the blade into a vertical position.

A weight is so connected with each blade as to hold it in a vertical position; but before 20 the force of the wind increases to such a degree as to endanger the wind-wheel the blade is turned toward a horizontal position, raising the weight and presenting less active surface to the wind. I also employ securing devices 25 for holding the blades in a horizontal position when it is desired to put the wheel out of action.

My invention further consists in details of construction to be hereinafter explained. 30 In the accompanying drawings, Figure 1 represents a side view, partly in section, of a wind-wheel embodying my invention and comprising two pairs of blades. Fig. 2 represents a plan thereof, and Fig. 3 represents a perspective view of a portion thereof upon an enlarged scale.

Similar letters of reference designate corresponding parts in all the figures. 40 A designates the main vertical shaft, which is rotated by the wheel; and B designates the blades, which are arranged in pairs, those of each pair being upon opposite sides of the shaft, and the pairs adjacent to each other are arranged at right angles to each other. 45 Though two pairs only are shown, four or even more pairs of blades might be arranged upon the shaft A.

The blades B may be composed of a frame of metal covered with canvas or other material, so as to make them as light as possible,

or they might be made of wood or sheet metal. The blades of each pair are arranged upon a transverse horizontal shaft, C, upon which they turn as an axis independently of each other, and such shafts are in this example of my invention supported in bearings *a* in or attached to a skeleton frame-work composed of channel-beams D, secured transversely upon opposite sides of the central shaft, A, and securely braced thereto by braces D', so as to resist 55 the force of the wind.

When the blades are turned into a vertical position, so as to present their faces to the wind, they are operative or active; but when turned upon their axes to a horizontal position 60 they are inactive.

Secured rigidly to the shaft A is a hub, E, which rotates therewith and is fitted to a bearing in the frame-work F, supporting the vertical shaft A. As here represented, this bearing is formed by a series of anti-friction rollers, *b*, supported in suitable journal-bearings in a hollow support or plate, F'.

Arranged about the vertical shaft A are a number of weights, G, adapted to slide vertically upon guide-rods *c* secured to the shaft A. Each of the weights G is connected to one of the blades B by means of a cord or other flexible connection, *d*, which passes upward from the weight over a pulley, *e*, secured 70 to the shaft A, thence over a pulley, *f*, secured to the end of a rod or arm, *g*, extending from the shafts C, and is secured to the blade near one edge thereof.

When the wind increases in violence to such 80 a degree as might endanger the safety of the wheel the blades B are turned upon their axes toward a horizontal position against the force exerted by the weights G, which are raised through the connections *d*, so that when in operation the blades always automatically adjust themselves so as to present the proper area of active surface to the wind.

The rods or arms *g* supporting the pulleys *f* have a bearing upon the shafts C, and in 90 order to prevent them from turning upon the shafts so far as to render the pulleys *f* inoperative I have shown stops *s*, projecting from the frame-work supporting the shafts, against which the arms or rods strike, and by which 95 100

said arms are prevented from moving past a vertical position.

It will be observed that the blades B have bearings upon the shafts C at one side of their center, so that the under side of the blade, which has the preponderating weight, always tends downward to a position at which it will take the wind, it being kept from turning past a vertical position by the weights G.

10 When the blades, by the rotation of the central shaft, are brought into a position at which the wind blows upon their reverse sides they are at once turned toward a horizontal position, and they are thus automatically brought 15 into a vertical or active position, and afterward turned toward a horizontal position to enable them to turn against the wind.

In order to enable any or all of the blades to be adjusted and held in a horizontal position so as to render them inoperative, I attach 20 to each blade a cord or other flexible connection, *i*, which is passed through a guide, *j*, or over a pulley, thence over a pulley, *k*, attached to the shaft A, and downward in proximity to 25 the said shaft. At the lower end each cord or connection *i* is provided with a ring or loop, *l*, which may be secured to a hook, *m*, upon the shaft A when it is desired to hold the blade to which it is attached in a horizontal 30 position to render it inoperative.

By my invention I produce a wind-wheel the blades of which automatically adjust themselves to suit the varying velocity of the wind, and in which the power of the blades is transmitted direct to the vertical shaft without the use of intermediate mechanism to increase the 35 friction of the apparatus.

What I claim as my invention, and desire to secure by Letters Patent, is—

40 1. The combination, in a wind-wheel, of a central vertical shaft, horizontal shafts extending transversely to said vertical shaft and supported thereby, and blades arranged upon said horizontal shafts at each side of the vertical shaft, each blade consisting of a single piece or surface pivoted to its horizontal shaft above its center, so that the blade will always

tend to assume a vertical position, and the several blades being all adapted to turn independently of each other, substantially as specified. 50

2. The combination, in a wind-wheel, of a central vertical shaft, horizontal shafts extending transversely to said vertical shaft and supported thereby, blades arranged upon said horizontal shafts at each side of the vertical shaft, each blade consisting of a single piece or surface pivoted to its horizontal shaft above its center, so that the blade will always tend to assume a vertical position, and cords attached to the blades and provided at their lower ends with weights, which tend to turn the blades into a horizontal position, substantially as specified. 55

3. The combination of the vertical shaft A, 60 the transverse frames composed of the channel-beams D, arranged in pairs, and braces D', the shafts C, supported in bearings *a*, and the blades B, supported upon said shafts and adapted to turn independently thereof, substantially as specified. 70

4. The combination of the vertical shaft A, having the hub E fixed thereon, the hollow plate F', the anti-friction rollers *b*, supported 75 therein, the transverse frames supported by the shaft A, the shafts C, and the blades B, adapted to turn upon said shaft independently of each other, substantially as specified. 80

5. The combination of the transverse frames D D', provided with stops *s*, the shafts C, and 85 blades B, the arms or rods *g*, adapted to turn upon said shafts and arranged to abut against stops *s*, the pulleys *e f*, the cords *d*, connected to the blades and passing over said pulleys, and the weights G, substantially as specified. 85

6. The combination of the transverse frames D D', the shafts C, and blades B, the guides *j*, the pulleys *k*, and the cords *i*, connected to the blades B and passing over said guides and pulleys, all substantially as specified.

JOEL SANDER.
